RADIO RECEIVER

Naoki Tominaga, Moriguchi-shi, Japan, assignor to Sanyo Electric Co., Ltd., Osaka, Japan

Filed Feb. 5, 1969, Ser. No. 15,659

Claims priority, application Japan Aug. 23, 1968

Term of patent 7 years

Int. Cl. D14—03

U.S. Cl. D56—4

FIG. 1

FIG. 3

FIG. 2

FIG. 4

FIG. 1 is a perspective view of the radio receiver of the present invention;

FIG. 2 is a front elevational view of the radio receiver shown in FIG. 1;

FIG. 3 is a rear elevational view of the radio receiver shown in FIG. 1; and

FIG. 4 is a side view of the radio receiver shown in FIG. 1, which has an identical opposite side view and identical top and bottom plan views.

The drawing figures are shaded to indicate contrast in appearance.

I claim:

The ornamental design for a radio receiver, as shown and described.
